A graphic design featuring two large, bold letters 'U' and 'S' in a black and white, high-contrast style. The letter 'U' is on the left, and the letter 'S' is on the right. Each letter has a small, thin 'a' mark at the top and a small 'x' mark inside the bowl of the 'U'. The letters are set against a white background with a black border around the entire image.

UNITED STATES PATENT OFFICE

THOMAS J. PETTIT AND C. CHRISTIAN RUSS, OF SAN FRANCISCO, CAL.

DESIGN FOR PRINTING-TYPES.

Specification forming part of Design No. **11,531**, dated December 2, 1879; application filed September 18, 1879.
[Term of patent 3½ years.]

To all whom it may concern:

Be it known that we, THOMAS JEFFERSON PETTIT and C. CHRISTIAN RUSS, of the city and county of San Francisco, and State of California, have originated a new Design for Types for Printing Posters, of which the following is a full, clear, and exact description, reference being had to the accompanying drawing, making a part of this specification.

Our design has relation to the shape or form of the letters; and it consists in forming tapering points at the tops and bottoms and middle portions of the letters. The side lines of the prominent parts of the letter are curved outward near the bottom and top, as at *b*, so as to widen that part of the letter. We then connect the ends of outward-curved lines by a double ogee line, which is made quite deep and bellying

downward, thus forming enlargements, which terminate at the top and bottom of the letters in a point, *C*. The middle portions of the letters are provided with tapering points *d*.

What we claim as our invention is—

A design for types for printing posters, in which the terminals at the bottoms and tops and the middle portions of the letters are provided with tapering points or extensions, substantially as shown and described.

In witness whereof we have hereunto set our hands and seals.

THOMAS JEFFERSON PETTIT. [L. S.]
C. CHRISTIAN RUSS. [L. S.]
